CLAIM

The ornamental design for a chair, as shown and described.

DESCRIPTION

FIG. 1 is a perspective view of a chair showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a front left perspective view thereof;

FIG. 9 is a front bottom perspective view thereof; and,

FIG. 10 is a rear bottom perspective view thereof.

The broken line showing wheels, legs, and fasteners is included for the purpose of illustrating environmental structure and forms no part of the claimed design.
